US00D861168S

(12) **United States Design Patent** (10) Patent No.: **US D861,168 S**
(45) Date of Patent: ** Sep. 24, 2019

(54) **WEARABLE FITNESS MONITOR**(71) Applicant: **Fitbit, Inc.**, San Francisco, CA (US)(72) Inventors: **Brian Dennis Paschke**, San Francisco, CA (US); **Jonah Avram Becker**, San Francisco, CA (US); **Chadwick John Harber**, San Francisco, CA (US); **Bernhard Wildner**, San Francisco, CA (US); **Eric John Fairbanks**, Lafayette, CA (US); **Cory William Worth**, Palo Alto, CA (US); **Dennis Jacob McCray**, San Diego, CA (US); **Ming-Sheng Ku**, Taipei (TW)(73) Assignee: **Fitbit, Inc.**, San Francisco, CA (US)(**) Term: **15 Years**(21) Appl. No.: **29/602,541**(22) Filed: **May 1, 2017**

(57) **CLAIM**

The ornamental design for a wearable fitness monitor, as shown and described.

DESCRIPTION

FIG. 1 is an isometric view of a wearable fitness monitor. FIG. 2 is a front view of the wearable fitness monitor of FIG. 1.

FIG. 3 is a back view of the wearable fitness monitor of FIG. 1.

FIG. 4 is a top view of the wearable fitness monitor of FIG. 1.

FIG. 5 is a bottom view of the wearable fitness monitor of FIG. 1.

FIG. 6 is a side view of the wearable fitness monitor of FIG. 1.

FIG. 7 is an opposite side view of the wearable fitness monitor of FIG. 1.

FIG. 8 is an off-angle view of the wearable fitness monitor of FIG. 1.

FIG. 9 is a different off-angle view of the wearable fitness monitor of FIG. 1.

FIG. 10 is an exploded view of the wearable fitness monitor of FIG. 1.

FIG. 11 is an isometric view of a wearable fitness monitor. FIG. 12 is a front view of the wearable fitness monitor of FIG. 11.

FIG. 13 is a back view of the wearable fitness monitor of FIG. 11.

FIG. 14 is a top view of the wearable fitness monitor of FIG. 11.

FIG. 15 is a bottom view of the wearable fitness monitor of FIG. 11.

FIG. 16 is a side view of the wearable fitness monitor of FIG. 11.

FIG. 17 is an opposite side view of the wearable fitness monitor of FIG. 11.

FIG. 18 is an off-angle view of the wearable fitness monitor of FIG. 11.

FIG. 19 is a different off-angle view of the wearable fitness monitor of FIG. 11; and,

FIG. 20 is an exploded view of the wearable fitness monitor of FIG. 11.

Stipple shading is used in all of the accompanying Figures to convey surface contouring and not texture. The features shown in broken lines in the drawing depict environmental subject matter only, and form no part of the claimed design.
